ATTORNEY

UNITED STATES PATENT OFFICE.

JOSEPH B. HEISER, OF WILLIAMSPORT, PENNSYLVANIA.

RADIATOR-TRANSPORTING APPARATUS.

Application filed January 29, 1927. Serial No. 164,610.

This invention relates to a device for transporting radiators.

An object of the invention is the provision of a device which may be readily applied to a radiator so that the radiator may be manually carried or moved over a floor.

A further object of the invention is the provision of a device for ready application to a radiator and in which said device is equipped with rollers whereby the radiator may be supported in a movable manner or the device may be employed for lifting the radiator or lifted on an end and wheeled into position.

15 A still further object of the invention is the provision of a device which may be readily applied to a radiator and by which it is possible for one mechanic to easily transfer or transport said radiator without 20 requiring the assistance of a helper for elevating or positioning said radiator.

This invention will be best understood from a consideration of the following detail description in view of the accompanying 25 drawings forming a part of the specification, nevertheless it is to be understood that the invention is not confined to the disclosure being susceptible of such changes and modifications which shall define no material 30 departure from the salient features of the invention as expressed in the appended claims.

In the drawings:—

35 Figure 1 is a view in perspective of a radiator showing my device supporting a radiator,

Figure 2 is a view in perspective of the supporting device constructed according to the principle of my invention,

40 Figure 3 is another view in perspective of the device shown in Fig. 2,

Figure 4 is a side view of a radiator showing one application of the supporting device,

45 Figure 5 is a side view of a radiator showing a different application of the supporting device,

Figure 6 is vertical section taken along the line 6—6 of Fig. 4,

50 Figure 7 is a fragmentary vertical section taken along the line 7—7 of Fig. 2, and

Figure 8 is a vertical section taken along the line 8—8 of Fig. 6.

Referring now particularly to the drawings

10 designates a radiator composed of sections 11 having hollow connecting bosses 12 which are adapted to be aligned. Each section is spaced from alternate sections by the bosses and is provided with vertical passages 13 to provide for the circulation of air. 55

The supporting, lifting and positioning device comprises a frame having arms 14 and 15 disposed in parallel relation and provided with laterally inturned portions 16 which connect vertical parallel portions 17 with the arms 14 or 15. The portions 17 are so spaced that they will be in close association with the sides of the radiator. 60

The parallel portions 17 of the arms are bent backwardly or downwardly at 18 and 70 in close contact with the portions 17 while providing eyes 19 to receive the ends of a bar 20. The portions 18 are extended laterally at 21 and connect a transverse bar 22 to the portion 18. The transverse bar forms 75 at times a fulcrum in one application of the device. It will be seen that the frame is formed of a one piece rod bent to shape.

A sleeve 23 is secured to the outer free end of arm 14 or 15. The sleeve at the outer 80 end receives the shank 24 of a castor 25. A pin 26 having an end seated within a groove 27 of the shank permits turning of the shank to facilitate transportation of the device and the radiator supported thereby. 85

Each sleeve has a radial passage 28 to receive an end of a radiator supporting bar 29. Intermediate the ends of the bar a V-shaped or curved portion 30 is provided to receive a pair of the aligned bosses 12 between an adjacent pair of sections of the radiator. The radiator resting on the members 30 are supported thereby. The bar 29 when not required for use may be removed after the cotter pins 31 having been released 95 from the diametrically disposed passages in the ends of the bar. The bar 20 may also be released from the eyes 19 after the cotter pins 32 have been removed from the diametrically disposed passages in the ends of 100 said bar.

A stabilizing pin or rod 33 adapted to be inserted within the vertical passage 13 of an end section is secured to the fulcruming rod or bar 22 by means of a clamp generally designated by the numeral 34. 105

The clamp consists of a strap bent intermediate the ends thereof to provide an eye

35 to receive the rod 22 and has a pair of parallel fingers 36 perforated at 37 to receive a reduced threaded portion 38 of the pin 33. A nut 39 is threaded onto the reduced portion 38 for clamping the fingers together and for rigidly securing the clamp and pin 33 to the bar 22.

From an inspection of the drawings it will be noted that the device may be applied 10 to a radiator in a number of different ways for transporting a radiator. As shown in Fig. 1, the castors 25 are placed upon the floor and the lower alined bosses 12 of the radiator adjacent one end are seated within 15 the curved portion 30 of the bar 29, the arms 14 and 15 being located in a vertical manner and adjacent a transverse space between the sections of the radiator. The rod 20 is inserted through the space and received by 20 the eyes 19 after which the cotter pins 32 are placed in position to retain said rod in place. The cotter pins 31 are likewise inserted in the passages in the end of the rod 29 thereby maintaining said rod in position. The bar 25 25 will be located beyond the outer face of an end section of the radiator. Stabilizing pin 33 is positioned within the vertical passage 13 and will aid in maintaining the supporting frame in supporting position 30 with the radiator. When a supporting frame is applied to the opposite ends of the radiator as described above the radiator may be wheeled along the floor as is illustrated in Fig. 1.

Referring to Fig. 4 it will be seen that a supporting frame is applied to one end of the radiator in the manner which has been previously described for supporting one end of the radiator. A supporting frame is then 40 applied to the opposite end of the radiator with the rod 20 located between the second space formed by the sections and with the arms 14 and 15 and more particularly the portion 17 in close association with the sides 45 of the radiator. The bar 20 contacts with the outer face of the end section and acts as a fulcrum when the frame is elevated manually. The frictional contact between the bars 20 and 22 with the sections of the radiator aid in maintaining the frame in rigid 50 relation with the radiator. In this position the frame shown at the left hand end of Fig. 4 is elevated manually and the radiator is then wheeled to the position desired. The 55 pin 33 aids in stabilizing the elevating frame with respect to the radiator.

The device also may be applied as shown in Fig. 5 and in which the pins 33 engage the metal of the sections of the radiator at 60 the upper end of the vertical slot 13 and the bars 20 and 22 engage portions of the radiator so that the radiator may be carried by two mechanics as illustrated.

It will be appreciated, however, that while 65 the device may be manually carried by sev-

eral mechanics, the supporting frame is particularly useful since one mechanic may transport a radiator as shown in Figs. 1 and 4 and without placing any strain on said mechanic.

70

I claim:—

1. A device for transporting radiators comprising a frame including a pair of spaced arms having return bent portions, the return bent portions forming with the 75 arms eyes, a bar received by the eyes, and a cross bar formed integrally with the return bent portions.

2. A device for transporting radiators comprising a frame including a pair of spaced arms having return bent portions, the return bent portions forming with the 80 arms eyes, a bar received by the eyes, a cross bar formed integrally with the return bent portions, and a supporting bar carried 85 by the arms adjacent the free ends thereof.

3. A device for transporting radiators comprising a frame including a pair of spaced arms having return bent portions, the return bent portions forming with the 90 arms eyes, a bar received by the eyes, a cross bar formed integrally with the return bent portions, and a supporting bar carried by the arms adjacent the free ends thereof, 95 said supporting bar having a V intermediate portion adapted to receive the bottom of the radiator.

4. A device for transporting radiators comprising a frame including a pair of spaced arms having return bent portions, the 100 return bent portions forming with the arms eyes, a bar received by the eyes, a cross bar formed integrally with the return bent portions, a supporting bar carried by the arms adjacent the free ends thereof, and rollers 105 mounted on the free ends of the arms.

5. A device for transporting radiators comprising a frame including a pair of spaced arms having return bent portions, the return bent portions forming with the 110 arms eyes, a removable bar received by the eyes, and a cross bar formed integrally with the return bent portions.

6. A device for transporting radiators comprising a frame including a pair of spaced arms having return bent portions, the return bent portions forming with the arms eyes, a bar received by the eyes, a cross bar formed integrally with the return bent portions, and a supporting bar removably carried by the arms adjacent the free ends 115 thereof.

7. A device for transporting radiators comprising a frame including a pair of spaced arms having return bent portions, the return bent portions forming with the arms eyes, a bar received by the eyes, a cross bar formed integrally with the return bent portions, a sleeve mounted on each free end of an arm and provided with a radial pas- 125

130

sage, and a radiator supporting bar having the ends thereof inserted in the radial passageways.

8. A device for transporting radiators and capable of assuming various positions with respect to the radiator comprising a pair of supporting arms adapted to engage opposite sides of the radiator, a bar carried by the ends of the arms and adapted to be received between a pair of sections of the 10 radiator, a transverse bar supported in spaced relation with the arms and inwardly

of the free ends of the arms, the ends of the arms being extended in a return bent portion along the arms and laterally outwardly and connected to the transverse bar, a pin supported by the transverse bar and adapted to be received by an end section of the radiator, the return bent portions and the extensions of the return bent portions 15 being adapted to embrace opposite sides of the radiator, and a rest connected to the opposite ends of the arms.

JOSEPH B. HEISER.
